Res. 540

Sherman S. Jewett, and
Francis H. Root, of Buffalo, N.Y.
Letters Patent No. 540. Dated Jan'y 25th 1853.

The schedule referred to in these Letters Patent and making part of the same
To all whom it may concern:

Be it known that we S. S. Jewett, and F. H. Root, of Buffalo, in the County of Erie and State of New York, have invented or produced a new and ornamental design for Cooking Stoves, of which the following is a full, clear and exact description, reference being had to the accompanying drawings forming part of this specification, in which

Figure 1, is a front elevation of the stove, and
Figure 2, a side view thereof -

The front plate (A) of the stove, on which the doors (B B) are hinged, is of parallelogramic form, embellished with mouldings along its edges or border and having an elongated oblong panel, above the said doors, bearing the inscription "Prairie Flower. No. 3."

The side plates of the stove are similarly edged, or bordered, with

14

Ms. 540

mouldings, and are fitted with a large oblong door C, bordered by a moulding consisting of an ovolu a, cavetto b, semi-round c, and convex band d, enclosing a parallelogrammic recess or inverse panel (whose shortest sides are vertical) adorned with a floral device of the configuration and arrangement represented in the drawings, consisting of a full blown central flower (e) shooting from a stem f, and surrounded with foliage terminating at either side with pendant flowers g.

A small door D, of oblong form but different proportions to the door C, is fitted on one side of the stove: this door (D) has its longest sides vertical and is bordered with moulding of similar configuration to that of the door C; the said border moulding enclosing an oblong recess adorned with a full blown flower (h), stem foliage and side bud i, as represented in figure I.

Having thus described our ornamental design for cooking Stoves, what we claim as new therein and desire to secure by letters patent, is The device "Prairie Flower" on the front plate; the arrangement and configuration of the floral device ornamenting the side door C, consisting of a full blow central flower (e), stems, foliage and pendant flowers (g), and the ornamental configuration of the smaller door D, as herein represented and described.

In testimony whereof we have hereunto subscribed our names,

Witnesses
